UNITED STATES PATENT OFFICE.

CHARLES E. MICHAUD, OF BROOKLYN, NEW YORK, ASSIGNOR TO THE H & D FOLSOM ARMS CO., OF NEW YORK, N. Y., A CORPORATION OF NEW JERSEY.

CARTRIDGE AND TWISTER HOLDER.

Application filed October 3, 1925. Serial No. 60,169.

The invention relates to police and military belt attachments for carrying a supply of cartridges and for supporting the twister forming part of the officer's equipment. 5 These attachments have heretofore been independent articles each adapted to be attached to the belt separately. Such separate attachment to and location upon the belt is 10 objectionable for the reason that the officer is likely to mistake one for the other in an emergency, resulting in a loss of valuable time at a possibly critical moment.

The object of the invention is to avoid the above difficulty by combining the two articles in one, so that the cartridges and twister are both presented conveniently for immediate availability and in a single selected location on the belt.

The invention consists in certain details of 20 construction and arrangement by which such combination is effected and the above objects attained, to be hereinafter described and claimed.

The accompanying drawings form a part 25 of this specification and show the invention as it has been carried out in practice.

Figure 1 is a front or face view of the combined holder in the closed condition; the belt, cartridges, and twister being shown in 30 dotted lines.

Figure 2 is a vertical section taken on the line 2—2 in Figure 1, with the belt, cartridges, and twister omitted.

Figure 3 is a face view of the empty 35 holder in the open condition.

Similar reference numerals indicate the same parts in all the figures.

The main portion of the holder as shown 40 comprises a single piece of leather cut to the desired shape and folded upon itself. The wide upper part of the back 5 of such main portion is folded forwardly and downwardly and secured by a line of stitches 6 along its edge, to form a long loop 7 through which 45 the belt 8, shown in dotted lines, extends and upon which the holder is slidably supported. On the front or outer face of the loop 7 is secured a longitudinally extended strip of leather pleated or gathered to produce a 50 series of vertical open pockets 9 each adapted to receive and removably retain a cartridge 10, as shown in dotted lines in Figure 1.

The lower portion of the back 5 is in the

form of a narrower tongue 11 adapted to be folded forwardly and upwardly and separately held in such folded condition by a snap-fastener, the stud member 12 of which is mounted on the front face of the back 5, and the socket member 13 on the extremity of the tongue 11. 55

At the centre of the bight 14 of the folded tongue is an opening 15 through which the chain 16 of the twister extends, while the transverse arms 17 are securely held in the bight 14. 60

Thus arranged the cartridges are presented for immediate extraction, and the twister held securely against accidental removal while easily and quickly released for service by simply grasping the free end of the 70 tongue 11 and breaking the frictional grip of the snap-fastener. 65

By mounting the cartridges and twister in a single article, either is instantly available without loss of time. 75

Although the body of the holder is shown and described as preferably formed of a single piece of leather, it will be understood that any suitable material may be employed and that such body may be of two or more 80 pieces reliably joined together.

I claim:—

1. An improved article of manufacture comprising in a unitary structure a belt loop to receive a belt with one face adapted to 85 support a plurality of pockets and a depending portion to form a tongue, said tongue being foldable upon itself and the fold having an opening for the passage of a ligament, said fold being adapted to support and receive a ligament-supporting member. 90

2. The holder described comprising in a unitary structure a portion folded upon itself to form a belt-loop, a tongue depending from said portion and formed integrally 95 therewith, said tongue foldable upon itself and having an opening formed in the bight of such fold and adapted to receive the chain of a twister inclosed in such fold, and separable means for securing the free end of said 100 tongue in the folded condition independent of the belt-receiving portion.

In testimony that I claim the invention above set forth I affix my signature hereto.

CHARLES E. MICHAUD.
